UNITED STATES PATENT OFFICE.

ALFRED G. F. KUROWSKI, OF BROOKLYN, NEW YORK, ASSIGNOR TO UNDERWOOD TYPE-WRITER COMPANY, OF NEW YORK, N. Y., A CORPORATION OF DELAWARE.

TYPEWRITING MACHINE.

Application filed February 5, 1924. Serial No. 690,705.

This invention relates to ribbon mechanism for typewriting machines, and more particularly to machines for writing checks or similar instruments and for making a 5 copy on a continuous record-sheet of a part of the matter typed on each check of a series.

In writing a check, it is customary to insert it in the typewriter and type a plurality of lines upon it. The first line consists 10 of the name of the payee and the numerals indicating the amount for which the check is drawn, and the other line or lines include a statement of the amount for which the check is drawn, spelled out in full, and possibly 15 other data. It is desirable to keep a condensed record of the checks by copying on a record-sheet the first typewritten line only of each check. With this end in view, there is provided, in addition to the usual 20 ribbon mechanism for writing on the faces of the checks, an auxiliary ribbon behind the checks but in front of the record-sheet, and mechanism is also provided to move the auxiliary ribbon to and from effective position 25 at the will of the operator. The auxiliary ribbon not only makes the condensed record of the checks, but it also prints upon the backs of the checks, which is advantageous, since an alteration of a check, to escape 30 detection, requires that erasures be made at the same point on the front and back of the check, and this without making a thin spot which would be noticeable when the check 35 is held up to the light.

In accordance with one feature of the invention, provision is made of a manually-operable handle arranged to be effective when moved in one direction to raise the auxiliary ribbon frame and thereby to move 40 the auxiliary ribbon to ineffective position, and to be effective at a single stroke when actuated in the reverse direction, to perform the dual function of feeding the auxiliary ribbon and of restoring it to effective position. 45

It is an important feature that such actuation of the handle causes the ribbon to be first fed while in its ineffective position and to be thereafter moved to its effective position, whereby the likelihood of smearing the work by such ribbon-feeding is avoided. To this end the ribbon-feeding mechanism is mounted upon the auxiliary ribbon frame to swing as a unit therewith, so that the ribbon

may be fed while in its ineffective position, 55 and the ribbon is arranged to be fed by a movement of the feeding mechanism relative to the ribbon frame. Provision is made of detent means for yieldingly holding the ribbon frame in ineffective position, said means 60 being powerful enough to prevent movement of the frame toward effective position until the ribbon-feeding mechanism has been moved relatively to the frame to feed the ribbon. 65

The handle and the mechanism operated by it are so arranged that the handle may also be operated to feed the ribbon when the ribbon is in its effective position, without moving it from said position. The ribbon 70 may therefore be fed at the beginning of each line in which it is to be used, even though the work is of a character to cause such lines to occur in succession. 75

A further feature of the invention relates 80 to novel ribbon-reversing mechanism of a very simple and efficient character. The ribbon-spools at the opposite ends of the platen may be driven for feeding the ribbon in opposite directions by ratchet-wheels attached to them, and these are driven by feed-pawls arranged to be reciprocated by a rock-shaft that is connected to the ribbon-feeding handle and extends from side to side of the auxiliary ribbon frame. A ribbon-reversing 85 shaft also extends across the auxiliary ribbon frame, and has projections or cams arranged to be brought alternatively into engagement with the feed-pawls simply by movement of a reversing handle to rock the 90 reversing shaft, the arrangement being such that the feed-pawl which is engaged by its associated projection on the reversing shaft is rendered inoperative. 95

Other features and advantages will hereinafter appear.

In the accompanying drawings, Figure 1 is a plan view of a part of a typewriting machine having the present improvements applied thereto. 100

Figure 2 is a front elevation of the same.

Figure 3 is a sectional side elevation as seen from the right end of the machine, showing the auxiliary ribbon effective and the parts in normal operative position. The 105 position of the ribbon raising and feeding handle when moved to feed the ribbon is indicated in dot-and-dash lines in this figure.

Figure 4 is a view similar to Figure 3, but showing the auxiliary ribbon frame swung to elevate the ribbon to ineffective position.

5 Figure 5 is a sectional side elevation as seen from the left end of the machine, showing the auxiliary ribbon-feeding mechanism set to wind the ribbon upon the left ribbon-spool.

10 Figure 6 is a view similar to Figure 5, but showing the auxiliary ribbon-feeding mechanism reversed.

15 Figure 7 is a fragmentary sectional detail top plan view, showing the mounting of the auxiliary ribbon frame and associated mechanism.

20 Figure 8 is a perspective view of a friction spool-retarding device.

25 Figure 9 is a perspective view, partly broken away, of the auxiliary ribbon frame, showing particularly the details of construction of the ribbon-feeding mechanism and the ribbon-reversing mechanism.

30 Figure 10 is a transverse vertical section through the left ribbon-spool and associated parts.

35 The typewriting machine to which the present improvements are applied is provided with the usual main ribbon 10, which is fed back and forth between spools (not shown) and is threaded through a ribbon-vibrator 11 between a type-guide (not shown) and a platen 12 in position to be struck by types 13 for making impressions on the paper in the machine. The platen 12 is rotatably mounted by means of a platen-axle 14 journaled in a platen-frame 15 in the usual manner. Paper-feed-rolls 16 co-operate with the platen for feeding the checks and a record-sheet line by line, and may be cast off by means (not shown) of the kind usually provided in Underwood typewriters.

40 An auxiliary ribbon 17 arranged to pass between the main ribbon 10 and the platen 12 to print upon the face of the record-sheet and upon the back of the check is carried by spools 18, which, together with ribbon operating and controlling mechanism, are mounted upon an auxiliary ribbon frame comprising end plates 19 and 20 and a connecting rock-shaft 21 journaled in brackets 22 secured to the ends 23 of the platen-frame.

45 The auxiliary ribbon 17 extends forward from each of the spools 18 over a guide-roller 24, through an inclined ribbon-guide slot 25 at the front of the end plate on which the spool is mounted, and thence across the front of the platen through a corresponding guide slot 25 at the opposite side of the machine.

50 Each of the auxiliary ribbon-spools 18 is mounted for rotation about a horizontal shaft 26, supported in a hub cap 27 secured to one of the end plates 19, 20. The spool 18 is retained upon the shaft 26 by a spring

55 brake 28 and a knurled nut 29 threaded onto a reduced end portion 30 of the shaft that presses the spring brake 28 firmly against the side of the ribbon-spool 18. The pressure of the brake 28 can be adjusted by turning the nut 29 to adjust the retardation effected by the brake and thus control the tension of the ribbon 17. A ratchet-wheel 31 is also rotatable upon the shaft 26, said ratchet-wheel being spaced from the spool 18 by a washer 32 on the shaft and having driving connection with the spool through a pin 33 on the ratchet-wheel 31 that fits into a recess 34 in the spool 18. The ratchet-wheel 31 has a hub portion 35 that extends through the end plate on which it is mounted, snugly fits within the hub cap 27 for rotation relatively thereto, and forms an extended support for the shaft 26. A screw 36, threaded into an end of the shaft 26, retains the shaft in position in the hub cap 27 and also secures in place an elbow-spring-member 37 which bears upon a finger 38 that extends through the side of the hub cap and rides in a circumferential groove 39 of the ratchet-wheel hub 35 to detain the ratchet-wheel 31 in place on the shaft 26 when the ribbon-spool 18 is removed from the shaft. Each of the end plates 19 and 20 is fast to a bushing 40, and each bushing 40, in turn, is made fast by a pin 41 to the rock-shaft 21. A hub 42, journaled on the bushing 40 at the right end of the rock-shaft 21, has fast upon it a handle 43 for feeding the auxiliary ribbon 17 and for raising the auxiliary ribbon to ineffective position by mechanism to be described.

60 The handle 43 has a limited free movement relative to the auxiliary ribbon frame for feeding the ribbon 17, it being arranged to be depressed to feed the ribbon, and to be restored to normal position relative to the auxiliary ribbon frame by a spring 44 connected to a pin 45 on the handle and to a pin 45^a on the inside of the end plate 20, the pin 45 extending through a slot 46 in the end plate 20. A screw 47, projecting from the outer face of the end plate 20, is positioned to engage the handle 43 to determine the normal position of the handle 43 relative to the end plate in its normal position. When the handle 43 is raised from the full-line position of Figure 3 to the position of Figure 4, it acts through the pin 45 and the screw 47 to turn the auxiliary ribbon frame 65 about the axis of the rock-shaft 21 and thereby to lift the auxiliary ribbon 17 to an ineffective position.

65 For determining the normal and ineffective positions of the auxiliary ribbon 17 and for detaining it in either of such positions, there may be fixed upon each of the bushings 40 a hub 48 having a cam member 49 fast upon it. These cam members 49 at the opposite ends of the shaft 21 act in unison,

and each comprises an upper recess 50 and a lower recess 51 with an intervening projection 52 for co-operating with a detent-roll 53 carried by an arm 54 pivoted on one of the brackets 22 and urged toward the cam 49 by a spring 55 connected to the arm 54 and to the bracket 22. The lower recesses 51 co-operate with the detent-rolls 53 to detain the auxiliary ribbon frame yieldingly in its normal position, while the upper recesses 50 co-operate with the detent-rolls to detain the auxiliary ribbon frame in its raised position.

When it is desired to lower the auxiliary ribbon 17 to its effective position, the handle 43 is depressed from the position shown in Figure 4. The detent-rolls 53 at first prevent rotation of the auxiliary ribbon frame while the pin 45 travels from the forward end of the slot 46 to the rear end thereof, and it is during this time that the feeding of the auxiliary ribbon 17 is effected, as will be explained presently. After the engagement of the pin 45 with the rear end of the slot 46, the auxiliary ribbon frame moves in unison with the handle 43 to effective position, the detent-roll 53 being forced outward from the recess 50, over the projection 52, and seating again in the recess 51.

The handle 43, as has been stated, serves not only to move the auxiliary ribbon frame between effective and ineffective positions, but, in the movement from ineffective to effective position, it also acts to feed the auxiliary ribbon 17 to bring a fresh portion thereof to the writing position. For this purpose, the handle 43 has a rearwardly-extending arm 56 which is connected by a pin 57 and crank 58 to a hollow shaft or sleeve 59 rotatably mounted on the rock-shaft 21 and extending substantially the full distance between the end plates 19 and 20. At its left end the hollow shaft 59 is connected by means of a crank 60 and pin 61 to a disk 62 fast to a hub 63 on the left bushing 40. The handle 43 has pivoted upon it a feed-pawl 64 for co-operation with the ratchet-wheel 31 that drives the right ribbon-spool 18, while the disk 62 has pivoted upon it a similar pawl 65 for co-operation with the ratchet-wheel 31 that drives the left ribbon-spool 18, said pawls 64 and 65 being urged toward their respective ratchet-wheels by springs 66 coiled around the pivots of said pawls. It will be evident that during the time when the handle 43 is moving in a counterclockwise direction (as viewed in Figure 3) relatively to the auxiliary ribbon frame, the pawls 64 and 65 will be rocked forward relatively to the ratchet-wheels 31, and that either of them, if permitted to engage its ratchet-wheel, will rotate the ratchet-wheel to effect a feeding movement of the auxiliary ribbon 17.

Provision is made of means for control-

ling the pawls 64 and 65 to cause them to be alternatively and selectively effective. For this purpose, a rock-shaft 67, journaled in the end plates 19 and 20, has fast upon it a cam 68 for engaging the tail 64^a of the pawl 64 to hold it out of engagement with its ratchet-wheel 31, and a second cam 69 for engaging the tail 65^a of the pawl 65 to hold it out of engagement with its ratchet-wheel 31. The tails of the pawls 64 and 65 have cam surfaces 70 upon them for engaging the cams 68 and 69, and these cam surfaces are designed to cause the disengaging cams 68 and 69 when effective to maintain their respective pawls 64 and 65 out of reach of the ratchet-wheels 31 throughout their full movements. The cams 68 and 69 are arranged in different angular positions on the rock-shaft 67, so that in one position of the shaft the cam 68 will be effective and the cam 69 will be ineffective, while in another position of the shaft the reverse will be true. The shaft 67 is yieldingly detained in either of said positions by means of a spring-detent 71 that bears against flats 72 and 73 on the shaft. The shaft 67 is arranged to be rocked between such positions by a reversing handle 74, journaled on the hub cap 27 of the left end plate and connected to the rock-shaft 67 by a link 75 and a crank-arm 76 fast on the shaft 67. The reversing handle 74 has an arcuate slot 77 in which a screw 78, threaded into the left end plate 19, is received to limit the movement of the reversing handle by engagement with the ends of the slot.

Back-stop pawls 79, mounted to swing about the axis of the rock-shaft 21 and urged toward the ratchet-wheels 31 by springs 80, serve to prevent retrograde movements of the ratchet-wheels. Each of these pawls 79 is located to be engaged by the feed-pawl of its ratchet-wheel and to be moved to and maintained in an ineffective position by said feed-pawl when the latter is thrown out of operation by the reversing mechanism.

It will now be understood that when the handle 43 is raised to move the auxiliary ribbon frame to ineffective position, the ribbon-feeding mechanism merely moves in unison with the auxiliary ribbon frame without affecting the feed or the tension of the ribbon 17, but that during the first part of the downward movement of the handle 43, that is, while the pin 45 is moving from the front end of the slot 46 to the rear end thereof, the auxiliary ribbon-spool 18 whose feed-pawl is effective is rotated to feed the ribbon. The continued downward movement of the handle 43 returns the auxiliary ribbon frame to effective position.

The ribbon 17 may also be fed without elevating the ribbon frame, merely by depressing the handle 43 from the full-line position

of Figure 3 to the dotted-line position of said figure. When the ribbon 17 has been fully wound onto one of the ribbon-spools 18, the reversing handle 74 may be moved to reverse the direction of feed of the ribbon, but this will not otherwise affect the mode of operation of the ribbon mechanism.

Variations may be resorted to within the scope of the invention, and portions of the improvements may be used without others.

Having thus described my invention, I claim:

1. In a typewriting machine having a main ribbon for writing upon an outside sheet, in combination, means disposing an auxiliary ribbon for writing upon an inside sheet, means for moving the auxiliary ribbon between ineffective and effective positions, and means operated concomitantly with the operation of said ribbon-moving means to move the auxiliary ribbon to effective position, to feed the auxiliary ribbon.
2. In a typewriting machine, the combination with a platen and writing instrumentalities, of a ribbon to co-operate therewith, means for selectively and indefinitely detaining said ribbon in effective or ineffective position with relation to said platen and writing instrumentalities during the operation of the latter, means for moving the ribbon from ineffective to effective position, and mechanism operated by said ribbon-moving means to feed the ribbon.
3. In a typewriting machine, the combination with a platen and writing instrumentalities, of a ribbon to co-operate therewith, a frame whereby the ribbon is carried, arranged for movement between effective and ineffective positions, an operating member for moving the ribbon frame between effective and ineffective positions, said operating member being movable through a limited range relatively to the ribbon frame, and mechanism operated by the operating member during such relative movement to feed the ribbon.
4. In a typewriting machine, the combination with a traveling carriage and a revolute platen journaled therein, of a ribbon frame mounted on the carriage for pivotal movement about an axis parallel to the axis of the platen, a ribbon carried by said frame, ribbon-feeding mechanism including spools carried by said frame and independent of the pivot of said frame, a handle, and ribbon-feeding connections operated thereby, both the handle and the connections being mounted concentrically with the axis of the ribbon frame, the ribbon-feeding connections extending from said frame axis to the ribbon-spools.
5. In a typewriting machine, the combination with a traveling carriage and a revolute platen journaled therein, of a ribbon frame mounted on the carriage, ribbon-spools carried by the frame, ribbon-feeding mechanism, ribbon-reversing mechanism, and means for swinging the ribbon frame, the ribbon-feeding mechanism and the ribbon-reversing mechanism in unison to move the ribbon to an ineffective position and at the same time to maintain the normal relationship between the ribbon and its feeding and reversing mechanisms.
6. In a typewriting machine, the combination with a platen and writing instrumentalities, of a ribbon to co-operate therewith, a ribbon frame carrying the ribbon, ribbon-feeding mechanism, a common pivot for the ribbon frame and the ribbon-feeding mechanism, and means for swinging the ribbon frame and the ribbon-feeding mechanism in unison about said pivot to move the ribbon to an ineffective position and at the same time to maintain the normal relationship of the ribbon and its feeding mechanism.
7. In a typewriting machine, the combination of a ribbon-supporting frame, a ribbon-spool, a shaft to support said ribbon-spool on said frame, ribbon-feeding means, ribbon-feed-reversing means including a rock-shaft settable to two positions, means to operate said rock-shaft, said last-named means including a reciprocable finger-piece, means to pivotally support said finger-piece on the ribbon-spool shaft, an arm on said rock-shaft, a link connecting said arm with said finger-piece, and a stop to limit the movement of the finger-piece in both directions to locate the rock-shaft in its proper positions, and a detent to hold said rock-shaft in either of its positions.
8. In a typewriting machine, a ribbon-feeding mechanism including a mounting plate, a hub fast to said plate and having an axial bore and a hole through its shell adjacent said plate, a ratchet-wheel, a hub fast to said ratchet-wheel and engaging in the bore of said mounting-plate hub, and having an annular groove in its periphery which registers with said hole in the shell of said mounting-plate hub, a pin passing through said hole and engaging in said groove, and a spring fastened to said mounting-plate hub and arranged for pressing inwardly on said pin.
9. In a typewriting machine, a ribbon, ribbon-feeding mechanism, and ribbon-retarding means to control the tension of the ribbon, said means including a ribbon-spool having a circular extension associated therewith, a bracket-plate to support said spool, a hub on said plate to receive said extension, a pin in said hub extending toward the center thereof and bearing against said extension, and a spring to press said pin against said extension.
10. In a typewriting machine, a ribbon mechanism including a shaft, a ratchet-wheel arranged with a hub portion for ro-

- uation on said shaft, ribbon-feeding means co-operating with the ratchet-wheel, a ribbon-spool also rotatable on the shaft and having driving connection with the ratchet-wheel, means for retaining the ribbon-spool in place on the shaft alongside the ratchet-wheel, and means for retaining the ratchet-wheel in place on the shaft when the ribbon-spool is removed therefrom, the ratchet-wheel-retaining means including a spring-pressed part bearing on said ratchet-wheel hub and tending to retard the rotation of the latter and said ribbon-spool.
11. In a typewriting machine, the combination with a platen and a platen-frame, of a unitary auxiliary ribbon device including a pair of detachable mounting plates, one at each end of said platen-frame, a rod fastened between said plates, a ribbon-frame supported on said rod and carrying an auxiliary ribbon to co-operate with said platen, means for swinging said ribbon-frame about said rod between effective and ineffective positions, a ribbon-feeding mechanism supported on said rod, and a ribbon-reversing mechanism supported on said mounting plates in the rear of said rod.
12. In a typewriting machine, the combination with a platen and writing instrumentalities, of a ribbon to co-operate therewith, a rod, a ribbon frame supported on said rod and on which the ribbon is mounted, means for swinging the ribbon frame to move the ribbon to ineffective position, and ribbon-feeding mechanism also mounted on said rod to swing in unison with the ribbon when the latter is moved to ineffective position.
13. In a typewriting machine, the combination with a main ribbon, of an auxiliary ribbon, means for rendering the auxiliary ribbon ineffective at the will of the operator, ribbon-feeding mechanism, a handle operable to actuate the ribbon-feeding mechanism to feed the auxiliary ribbon when said ribbon is in effective position, and means operable by said handle to move the auxiliary ribbon from ineffective to effective position.
14. In a typewriting machine, the combination of a ribbon-supporting frame, ribbon-spools on said frame, ribbon-feeding means including ratchet-wheels connected to the ribbon-spools, pivoted feed-pawls to engage said ratchet-wheels one at a time, ribbon-feed-reversing means including a rock-shaft settable to two angular positions to render either pawl effective while the other pawl is being rendered ineffective, means to turn said rock-shaft, pivoted back pawls, one for each ratchet-wheel, and springs to hold said back pawls in engagement with said ratchet-wheels, the forward ends of said feed-pawls engaging with said back pawls adjacent their pivots, so that when either feed-pawl is swung out of effective position, the associated back pawl is rendered ineffective thereby.
15. In a typewriting machine having a carriage, a ribbon-feeding mechanism including a pair of ribbon-spools, one at each side of the carriage and onto which a ribbon is alternately wound, a laterally-disposed rod, a pair of ratchet-wheels, each ratchet-wheel having driving connection with one of the spools, a pair of pawls, one for each ratchet-wheel to feed it step by step, means including reciprocable flange members supported on said rod and on which the pawls are carried and whereby they are reciprocated in unison to actuate the ratchet-wheels and feed the ribbon, and reversing mechanism including a rotatable rock-shaft and cams thereon to engage the pawls and render them ineffective alternately.
16. In a typewriting machine having a carriage, ribbon-feeding mechanism on said carriage including a pair of ribbon-spools onto which a ribbon is alternately wound, a pair of ratchet-wheels, each ratchet-wheel having driving connection with one of the spools, a rod parallel with said ribbon in the rear thereof, a pair of pawls, having rearwardly-extending tail portions, one pawl for each ratchet-wheel to feed it step by step, and reciprocable members on said rod on which the pawls are carried and whereby they are reciprocated in unison, a rock-shaft in the rear of said rod, a pair of pawl-disengaging cams on the rock-shaft, one for co-operation with each tail portion, and means movable at right angles to the travel of said carriage to rotate said rock-shaft to render said pawls effective alternatively by said cams.
17. In a typewriting machine, a ribbon, ribbon-feeding mechanism including a pair of ribbon-spools onto which the ribbon is alternately wound, a pair of ratchet-wheels, each ratchet-wheel having driving connection with one of the spools, a pair of pawls, one for each ratchet-wheel to feed it step by step, and a reciprocable frame on which the pawls are pivoted and whereby they are reciprocated in unison, and reversing mechanism including a rock-shaft extending parallel to the pivots of the pawls and arranged to one side thereof, disabling cams on said rock-shaft to engage the pawls and render them inoperative alternatively, and cam-surfaces on the pawls for co-operation with the disabling cams, said surfaces being arranged on the same side of the pivots, and the cams on the rock-shaft being offset circumferentially, so that a pawl held initially out of engagement with its ratchet-wheel by its disabling cam will be rendered effective while the other pawl is being rendered ineffective.
18. In a typewriting machine, a ribbon-

feeding mechanism including a laterally-disposed rod, a rocking frame pivoted about said rod, a pivot-pin oscillatable about said rod, a feed-pawl on said pivot-pin, a ratchet-wheel on said frame arranged to be fed step by step by the feed-pawl, a ribbon-spool on said frame driven by the ratchet-wheel to feed a ribbon, and a back-stop pawl to prevent retrograde movement of the ratchet-wheel, said back-stop pawl being pivoted concentrically with the rocking frame and therefore relatively stationary during the reciprocation of the feed-pawl.

19. In a typewriting machine, in combination, a ribbon, ribbon-feeding mechanism, and ribbon-reversing mechanism comprising a rock-shaft and mechanism carried thereby effective in one position to cause the ribbon to be fed in one direction and in another position to cause the ribbon to be fed in the opposite direction, a handle to operate said rock-shaft, means to engage said handle for positively arresting the movement of the rock-shaft in said positions, and means engaging said rock-shaft for yieldingly detaining the rock-shaft in said positions.

20. In a typewriting machine, in combination, a ribbon, a ribbon frame swingable to move the ribbon between effective and ineffective positions, ribbon-feeding mechanism, ribbon-reversing mechanism carried by said frame, comprising a rock-shaft, means for detaining the rock-shaft in a position to cause the ribbon to be fed in one direction, and in another position to cause the ribbon to be fed in the opposite direction, a handle carried by the ribbon-frame and connected to the rock-shaft for moving it between said two positions, and means to limit the extent of movement of the handle to arrest it in one direction when the rock-shaft has reached one of said positions and in the other direction when the rock-shaft has reached the other of said positions.

21. In a typewriting machine, the combination of a ribbon-supporting frame including two end plates, a rod connecting said end plates to each other, feed mechanism including ratchet-wheels, one at each side of said frame, pawls to engage said ratchet-wheels, one at a time, reciprocal supports for said pawls, said supports being mounted on said rod and located outside of the end plates, connecting means between said pawl-supports, said connecting means including a sleeve on said rod, said sleeve being located between said end plates, arms on said sleeve, and lateral extensions connecting said arms with said pawl-supports, said lateral extensions being located beyond the edges of the end plates, and means to reciprocate said supports to feed the ribbon.

22. In a typewriting machine, in combination, a ribbon-carrying frame, actuating means to operate said frame to render the

ribbon effective and ineffective, detent means to hold said frame either effective or ineffective, and ribbon-feeding mechanism, said actuating means having a movement independent of the ribbon-frame to actuate the ribbon-feeding mechanism while the ribbon-frame is held by said detent means, said actuating means being subsequently effective to actuate said ribbon-frame.

23. In a typewriting machine having a platen-frame, in combination, two mounting plates on said platen-frame, a rock-shaft between said mounting plates, a frame including plates fastened to the rock-shaft for carrying a ribbon, a handle for rocking the rock-shaft to move the ribbon to effective or ineffective position, notched elements fixed to the rock-shaft, spring-pressed detents on said mounting plates to co-operate with the notches in said elements to retain the ribbon in its effective or ineffective position, and stops on said notched elements to co-operate with said detents to prevent overthrow of the ribbon-frame when said frame is operated by said handle.

24. In a typewriting machine having a platen-frame, in combination, a rod disposed between the ends of said platen-frame, a reciprocable ribbon-carrying frame pivoted on said rod to move the ribbon to and from effective position, ribbon-feeding mechanism on said rod, a pivoted handle for operating the ribbon-feeding mechanism and for moving the ribbon-frame to make the ribbon effective or ineffective, a lost-motion connection between the handle and said ribbon-frame, and means yieldingly detaining the ribbon-frame in its ineffective position while said handle is being operated and until the feeding of the ribbon has been substantially completed.

25. In a typewriting machine, the combination with a platen and writing instrumentalities to print through a ribbon, of means to move said ribbon to and from effective position adjacent the platen, and means operable at a single stroke to feed the ribbon while in its ineffective position and then to move the ribbon toward the platen to its effective position after the ribbon-feeding has been substantially completed.

26. In a typewriting machine, the combination with a platen-frame, of an auxiliary ribbon mechanism including detachable mounting plates on said platen-frame, a rod between said plates, an auxiliary ribbon-carrying frame on said rod reciprocable between positions to make the ribbon effective and ineffective, ribbon-feeding instrumentalities on said rod, a rotatable shaft in the rear of said rod, ribbon-reversing instrumentalities on said shaft, and means carried by said mounting plates for latching the ribbon-frame in ineffective position a short distance above the printing line, said rod

and said shaft engaging with said mounting plates so as to brace said auxiliary ribbon mechanism and permit it to be readily attached or detached as a unit.

27. In a typewriting machine, the combination of a ribbon-supporting frame including two end plates, a rod connecting said end plates to each other, feed mechanism including ratchet-wheels, one at each side of said frame, pawls to engage said ratchet-wheels, one at a time, reciprocatory supports for said pawls, said supports being mounted on said rod and located outside of the end plates, connecting means between said pawl supports, said connecting means including a sleeve on said rod, said sleeve being located between said end plates, arms on said sleeve, and lateral extensions connecting said arms with said pawl-supports, said lateral extensions being located beyond the edges of the end plates, means to reciprocate said supports to feed the ribbon, ribbon-reversing means including a rock-shaft, a finger-piece to reciprocate the latter, tails on said pawls, and cams on said rock-shaft to engage said tails, said cams being arranged in different radial positions, so that when the shaft is rocked, one cam renders its associated pawl ineffective with one of the ratchet-wheels while the other cam renders its associated pawl effective with the other ratchet-wheel.

28. In a typewriting machine, a ribbon-feeding mechanism including a ratchet-wheel, a hub on said ratchet-wheel having an axial bore and an annular groove in its outer periphery, a mounting plate adjacent said ratchet-wheel, a hub fast on said mounting

plate and having an axial bore to receive said ratchet-wheel hub, and having a hole through its shell registering with said annular groove, a stub-shaft having a flange-portion disposed adjacent one end and arranged for fitting snugly in said mounting-plate hub, and a body-portion arranged for said ratchet-wheel hub to engage therearound, a screw extending through the end of said mounting-plate hub and threaded into the end of said stub-shaft for holding the latter fast to said mounting-plate hub and against rotation, a pin extending through the hole in said mounting-plate hub and resting in said annular groove to retain said ratchet-wheel in place, a spring releasably held by said screw and engaging said pin to press it against said ratchet-wheel hub, and a ribbon-spool on said stub-shaft operatively connected to said ratchet-wheel.

29. In a typewriting machine, a ribbon-spool-drive mechanism including a ratchet-wheel, an axle disposed adjacent said ratchet-wheel and parallel to the axis thereof, a member on said axle mounted for rotation therearound, a driving pawl pivoted on said member for engaging the teeth of said ratchet-wheel, and a back-stop pawl pivoted on said axle and disposed so that the back side of the front end of the drive pawl is in close proximity to said back-stop pawl intermediate its front end and said axle, whereby a small rotary movement of said drive pawl about its pivot will move said back-stop pawl to ineffective position.
